Filed Sept. 18, 1959, Ser. No. 57,606

Term of patent 14 years

(Cl. D34—5)

FIG. 1

FIG. 2

FIG. 3

FIG. 4

Fig. 1 is a perspective view of a golf club head showing my new design.

Fig. 2 is a side elevation of the golf club head according to Fig. 1.

Fig. 3 is a frontal elevation of the golf club head according to Fig. 1.

Fig. 4 is a plan view of the golf club head according to Fig. 1.

The characteristic feature of my design resides in the combination on the golf club head disclosed of the spirit level indicator imbedded in the club head along the top edge away from the face portion, substantially as shown.

I claim:

The ornamental design for a golf club head substantially as shown and described.
